UNITED STATES PATENT OFFICE.

KARL SIEBEL, OF KIEL, GERMANY, ASSIGNOR TO THE FIRM: NEUFELDT & KUHNKE,
BETRIEBSGESELLSCHAFT M. B. H., OF KIEL, GERMANY.

TELEPHONE RECEIVER.

Application filed November 18, 1924, Serial No. 750,564, and in Germany November 30, 1923.

This invention relates to improvements in telephone receivers and has for its object to simplify the construction of telephones, thus reducing the manufacturing cost, without sacrificing the good quality of the telephones.

According to the invention a three pole magnet in form of a prism with two portions cut out from one longitudinal side is employed in connection with a magnetic diaphragm, the two external poles of the magnet either making contact directly with the peripheral portion of the diaphragm or making contact with a thin ring of sheet-iron interposed between the diaphragm and such poles.

This construction possesses very good magnetic properties and is particularly favourable for the fitting on of the coil.

Also, the magnet structure is capable of being produced very easily.

An example of a telephone constructed in accordance with the invention is illustrated by the accompanying drawing, in which

Figure 1 is a plan of a telephone receiver casing containing a three pole magnet constructed in accordance with these improvements.

Figure 2 is a section on the line A—B of Figure 1 but in this section a polar ring is shown in contact with the external poles and a diaphragm in contact with the ring.

1 is the case of the telephone, and 2 is the three-pole magnet, consisting of four laminae produced by punching or stamping from sheet steel, thus rendering the manufacture easy. 3 and 4 are the external poles of like polarity, and 5 is the central pole of opposite polarity, this pole 5 being adapted for the mounting of a coil.

In Figure 2, 6 is a distance-ring of soft iron, in contact with the two external poles 3 and 4, the diaphragm 7 lying against the distance-ring. The iron-ring 6 is easily produced by punching or stamping. By this iron-ring the distance between the diaphragm and the pole 5 is exactly fixed, provided that the faces of the three poles 3—5 are level, which may be obtained easily by grinding top of the telephone-case with the magnet mounted in it.

The distance-ring 6 may of course be exchanged for two iron-plates, laid on the poles

3 and 4, but this is not to be recommended as in this case devices must be provided for fastening the diaphragm around the whole periphery. Also, the diaphragm may be placed directly in contact with the faces of the poles 3 and 4. In this case, the inner pole 5 must be shortened, for instance by appropriate manipulation of the grinding disc or tool.

According to experience, the sensitiveness and receiving quality of a telephone comprising these improvements equals and often surpasses similar qualities of telephones at present in use. The manufacturing costs are extremely low as compared with those of other telephones. The telephone-magnet, usually of a complicated shape, composed of several pieces, consists according to this invention only of an assemblage of laminae, stamped out of sheet steel. Instead of the two coils heretofore commonly used, only one coil is necessary for the magnet hereinbefore described. The manufacture of the telephone, especially in accordance with Figure 2, is quite simple, all poles of the magnet being level with the edge of the case and being ground by one and the same operation. A ring 6 stamped out of thin sheet iron not only magnetically connects the external poles and the diaphragm, but at the same time serves to adjust the centre of the diaphragm in relation to the central pole.

I claim:

1. A telephone having a casing containing a three pole magnet comprising a prismatic magnet body recessed at two places on its upper longitudinal side to form one central pole and two external poles, and a magnetic diaphragm having its peripheral portions in magnetic contact with the external poles of said magnet.

2. A telephone having a casing containing a three pole magnet comprising a prismatic magnet body recessed at two places on its upper longitudinal side to form one central pole and two external poles, a magnetic spacing ring covering the external poles and a magnetic diaphragm on said ring having magnetic contact with said poles at its peripheral portions thru said ring.

In testimony whereof I affix my signature.

KARL SIEBEL.
